UNITED STATES PATENT OFFICE

156,573

CIGARETTE LIGHTER

Gerald Stahl, Rye, N. Y.

Application June 18, 1948, Serial No. 147,050

Term of patent 3½ years

(Cl. D48—27)

To all whom it may concern:

Be it known that I, Gerald Stahl, a citizen of the United States and residing at Rye, in the county of Westchester and State of New York, have invented a new, original, and ornamental Design for a Cigarette Lighter, of which the following is a specification, reference being had to the accompanying drawings, forming part thereof.

Fig. 1 is a perspective view of a cigarette lighter, showing my new design; Fig. 2 is a top plan view thereof; Fig. 3 is an end elevational view, and Fig. 4 is a bottom elevational view.

The cigarette lighter is symmetrical so that the side of the lighter opposite that shown in Fig. 1 has the same appearance as the illustrated side.

I claim:

The ornamental design for a cigarette lighter, as shown and described.

GERALD STAHL.
